UNITED STATES PATENT OFFICE

CLARENCE D. TUSKA, OF HARTFORD, CONNECTICUT, ASSIGNOR, BY MESNE ASSIGNMENTS, TO RADIO CORPORATION OF AMERICA, A CORPORATION OF DELAWARE

RADIOCABINET

Application filed August 7, 1924, Serial No. 730,712. Renewed February 16, 1929.

This invention relates to radio cabinets of the type wherein the radio receiving set, together with a loud speaker horn and receiver are housed in a single cabinet unit.

5 One object of the present invention is to provide a radio cabinet wherein the receiving set and the horn and receiver are neatly and compactly arranged in a single compartment so that a minimum amount of space is 10 required.

Another object is to construct a radio cabinet of the above type so that the radio set is freely accessible with the least amount of difficulty and inconvenience.

15 A further object is to provide a radio cabinet of neat and attractive proportions due to the arrangement and construction of the various elements contained therein.

In the accompanying drawings and the 20 following description a preferred embodiment is illustrated and described from which the invention will be readily understood.

In the drawings,

Fig. 1 is a front view of my improved cabinet,

25 Fig. 2 is a side view of the same showing by dotted lines the arrangement of the different parts housed therein, and

Fig. 3 is a side view similar to Fig. 2 but 30 with the cover in raised position.

Referring to the drawings, 1, represents the lower part or stand of the cabinet and 2 is the upper part or housing compartment proper. In the present embodiment, I have 35 shown the stand 1 and compartment 2 constructed as a single unit but it will readily be understood that these parts may be constructed separately with the compartment 2 being removably supported upon the stand 1 40 or other similar support. The stand 1 is preferably constructed with a compartment therein having doors 6 hinged at either side to provide a convenient closed storage space for batteries 7 as shown by the dotted lines 45 in Fig. 2.

The front wall of the housing compartment 2 consists of two sections 8 and 10. The upper section 8 is preferably constructed of any attractively designed open scroll work 50 at the rear of which is a screen 9 of silk or

other similar material which will allow sound waves to pass freely therethrough.

The lower section 10 consists of the front panel of the radio receiving set 3 housed within the compartment 2; the radio set 3 55 being preferably constructed so that it is removably secured in the compartment 2.

The rear wall of the compartment 2 is also divided into two sections 11 and 12. The lower section 12 is a fixed part of the compartment 2 while the upper section 11 is secured to the lower section 12 by means of hinges 13 which are provided with stops to limit the rearward hinged movement of this upper section 11. A top cover 14 is fixedly 60 secured to the top edge of the upper section 11 which by means of the hinged section 11 provides a rearwardly opened top cover for the cabinet.

A loud speaker horn 4 and reproducer unit 5 are secured to the inside of the hinged portion of the compartment preferably by means of a strap or clamp 16 passing around the reduced or throat portion of the horn and fixed to the upper hinged portion 11 of the 65 rear wall. Resilient lugs or bumpers 15 are preferably interposed between the different portions of the horn and the hinged portion of the compartment in order to space the horn slightly from the hinged portion and prevent these portions of the horn from vibrating thereagainst. The mouth portion of the horn is thereby held closely adjacent the top cover 14 while the reduced or throat portion is adjacent the upper hinged portion. The horn 4 is of such a shape that the periphery of its flaring mouth is closely adjacent to and registers approximately with upper portion 8 of the front wall when the cover is in closed portion as shown in Fig. 2. 70 The reproducer unit 5 of the horn is connected to the radio set 3 by a flexible electrical connection 17 to allow for the opening movement of the cover as clearly shown in Fig. 3.

90 The cabinet is preferably provided with a folding front cover 18 which is hingedly secured to the lower front edge of the compartment 2; this front cover being provided with hangers 19 to support the same in a horizontal 95 100

position as shown in Fig. 2, whereby it serves as a shelf or desk surface for the operator of the radio set and may be closed up when the cabinet is not in use.

5 In the use of a radio cabinet of this character for housing a radio set it is preferable to have the sound issue from the upper part of the cabinet and this necessitates mounting the loud speaker horn above the set. Heretofore such a mounting for the horn has been objectionable by reason of the fact that it renders the parts of the set, such as tubes, connections, etc., inaccessible from the top of the cabinet. But by mounting the horn 10 as herein shown upon the cover of the cabinet it may be swung out of the way for giving convenient access to the set at all times. Furthermore, by the novel arrangement of the horn and receiving set in the cabinet a 15 minimum amount of space is required thereby reducing the dimensions of the cabinet and allowing an attractive and well balanced unit cabinet to be designed.

I claim:

25 1. A radio receiving cabinet comprising a compartment, a swinging door closing one side of the compartment, a radio operating panel positioned immediately back of the door and rising for a portion only of the 30 height of the compartment, a sound-transmitting grille positioned back of the door above the panel, an L-shaped cover hinged at the back of the compartment at a point substantially opposite the junction of the grille 35 and panel, an amplifying horn attached to the L-shaped cover and positioned thereupon so that when the cover is closed the opening of the horn is immediately back of the grille, a radio receiving set located back of the panel 40 and exposed by the swinging upwardly of the L-shaped cover, and a flexible operating connection between the receiving set and the horn whereby audible operation of the set may be continued when the set is exposed by 45 the lifting of the cover.

2. In a radio receiving cabinet provided with a compartment and including a pivotable door closing one side of the compartment, said side including a radio operating panel 50 positioned behind the door, and a grille positioned behind the door above the panel, in combination, a cover hinged at the back of the compartment, an amplifying horn attached to the cover and positioned thereupon so that 55 when the cover is closed the opening of the horn is behind the grille, a radio receiving set positioned behind the panel and adapted to be exposed when the cover is swung upwardly, and an operating connection between the set 60 and horn whereby audible operation of the set may be continued when the cover is lifted.

3. In a radio receiving cabinet provided with a compartment and including a pivotable door hinged to one side of the compartment, said side including a radio operating 65

panel positioned behind the door, and a grille positioned behind the door above the panel, in combination, a cover hinged at the side of the compartment opposite the pivotable door, an amplifying device attached to the cover and so positioned relative thereto that when the cover is closed the device is adjacent the grille, a radio receiving set positioned behind the panel and adapted to be exposed when the cover is swung upwardly, and a flexible operating connection between the set and amplifying device whereby audible operation of the set may be continued when the cover is lifted.

4. In a radio receiving cabinet provided with a compartment having an open side, means covering said open side, and a grille positioned above said radio receiving set and forming a portion of said side, the combination therewith of means pivotally mounted on said cabinet, sound amplifying means operatively connected to said radio receiving set and secured to said pivotally mounted means, said pivotally mounted means and amplifying means having closed and open positions such that when in closed position, said amplifying means is positioned adjacent said grille whereby sound may pass from said amplifying means through said grille, and when in open position, sound may pass from said amplifying means directly into the atmosphere.

5. In a radio receiving cabinet, in combination, a radio panel and a grille positioned above said panel forming a side of said cabinet, means pivotally mounted on said cabinet having a closed position and adapted when in closed position to overlie said grille, sound amplifying means secured to said pivotally mounted means and adapted to transmit sound through said grille when said pivotally mounted means is in closed position, said amplifying means being also adapted to transmit sound directly to the atmosphere when said pivotally mounted means is in any position other than its closed position.

In testimony whereof I have affixed my signature.

CLARENCE D. TUSKA.
